Attorney

UNITED STATES PATENT OFFICE

IVY SESSIONS, OF OAKLAND, CALIFORNIA

GARMENT HANGER

Application filed September 30, 1931. Serial No. 588,084.

This invention relates to certain new and useful improvements in garment hangers and the primary object of the invention is to provide a hanger especially adapted for supporting ladies' thin and flimsy dresses and similar wearing apparel, the said hanger according to the present invention being equipped with means throughout the full length of the hanger and adapted to be engaged by the garment, so that the latter will not be accidentally detached or displaced relative to the hanger when the latter is being manipulated as for example when placing the hanger on a rack, or when rotating the hanger as is often done in displaying the article suspended from the hanger.

A further object of the invention is to provide a garment hanger equipped with means whereby the garment will be held against displacement relative to the hanger either longitudinally or laterally with respect thereto.

Other objects and advantages of the invention will become apparent from a study of the following description, taken in connection with the accompanying drawing wherein:

Figure 1 is a side elevational view of the hanger, and

Figure 2 is a plan view of a portion of a garment retaining element with which the hanger is equipped.

Referring to the drawing it will be seen that the invention is applied to a conventional type of garment hanger designated by the reference character 5, and including a hook rising from an arcuate bar 6 such as are employed for supporting the dress or particular garment from the hanger, the ends of which bar 6 is connected by a horizontal bar 7 such as is used for supporting a garment in a folded position from the hanger as for example a pair of pants or the like.

The upper surface of the bar 6 for the full length of the bar, is covered by a strip 8, and the upper surface of the horizontal bar 7 for the full length of the bar is also covered by a similar strip 9. Each of the strips 8 and 9 are preferably of rubber and may be adhesively or otherwise secured to its bar.

Each of the strips 8, 9 on its upper surface is provided with a plurality of integral protuberances or teats 10, the teats being arranged in two longitudinal series with the teats of one series staggered relative to the teats of the second series as suggested in Figure 1.

From the above, it will be apparent that when a garment such as a dress is placed upon the hanger, the flexible protuberances or teats 10 of the strip 8 will engage the garment thus retaining the same against displacement either longitudinally or laterally relative to the hanger even though the hanger be rotated either in horizontal or vertical planes. Likewise, a garment such as a pair of pants or the like may be passed between the bars 6 and 7 and the protuberances or teats 10 on the strip 9 will engage the garment and likewise retain the same against displacement even though the garment be manipulated in the manner above suggested.

From the foregoing it will be seen that a garment hanger embodying the feature of the present invention will be especially adaptable for use in stores and the like since the same will serve admirably for suspending a garment in position to be readily examined by a prospective customer. As shown, the teeth, protuberances or teats are disposed at an angle to the perpendicular, with the teeth on one side of the transverse median of each strip being inclined oppositely to the teeth of the other side of said transverse median, and in providing such series of oppositely inclined teeth, the use of each strip and its associated teeth, for preventing displacement of a garment longitudinally of the hanger is materially enhanced.

Even though I have herein shown and described the preferred embodiment of the invention, it is to be understood that the same is susceptible of further changes, modifications and improvements coming within the scope of the appended claim.

Having thus described my invention, what I claim as new is:

A garment hanger including an arcuate bar, and a relatively straight bar connecting the ends of the arcuate bar, and each of said

bars including a supporting surface of resilient elastic material having staggeredly arranged inclined teeth of similar material projecting upwardly therefrom, the teeth on one side of the transverse median of each surface being inclined oppositely to the teeth on the other side of said transverse median.

5 In testimony whereof I affix my signature.
IVY SESSIONS.
